DESIGN FOR A PORTABLE BARBECUE COOKER

Erryl G. Eggleston, South Gate, Calif.

Application July 6, 1943, Serial No. 110,617

Term of patent 14 years

(Cl. D81—10)

To all whom it may concern:

Be it known that I, Erryl G. Eggleston, a citizen of the United States, residing at South Gate, county of Los Angeles, State of California, have invented a new, original, and ornamental Design for a Portable Barbecue Cooker, of which the following is a specification, reference being had to the accompanying drawing, forming a part thereof.

The figure is a view in perspective of a portable barbecue cooker showing my new design, it being understood that the opposite side of the article is identical with that shown.

I claim:

The ornamental design for a portable barbecue cooker, as shown and described.

ERRYL G. EGGLESTON.
